GEORGE B. VON ALVENSLEBEN, OF EUREKA, CALIFORNIA

LESSON MARKER AND MEANS OF HOLDING IN BOOK

Application filed March 22, 1932. Serial No. 600,472.

This invention relates to an improvement in a detachable type bookmarker and holder for said marker.

Today, many students of various books, such as the Bible, find it necessary, in connection with their study thereof, to mark certain oft-read passages, and to change these markings frequently when new passages are to be studied. It has long been the object of various devices to provide a marker which can be readily removed from one place in the book, and inserted in another place, but prior to the present invention, there has not been developed as efficient a marker as that provided for herein.

With markers of the prior art of the general type herein described, it has been necessary to thread through holes or slots in the tops of the several markers a rubber band or other flexible member. Considerable time is consumed on each occasion when it is desired to change the location of a single marker, or a group, because the flexible lacing must be untied or otherwise unfastened and pulled through the openings, and then, when they are in place again, it must be fed through them, usually with a needle, and retied. The markers slide between the pages and get out of line, adding difficulty and confusion to the process of relocating the markers and threading the holding means through each end. Further difficulty with markers of the prior art of this general type has been that the attaching means has pulled the marker deep into the space between the leaves until it was flush against the binding, causing a detrimental bulging of the book at the binding.

This bulging and distortion of the leaves at the binding causes a rapid deterioration of the book. Leaves become loosened and fall out.

It is the object of the present invention to provide a bookmarker set having holding means which are normally in place at the top and bottom of the book binding and are not removed when changing the position of the markers, to provide a marker holding means which holds the markers away from the binding of the book and prevents injury thereto,

to provide a marker holding means which is easily attached to and removed from books and when in position, forms an integral part of the book binding, to provide a marker holding means with the holding bar shaped to guide the marker when the leaves of the book open and close, to provide a marker shaped so as to present the minimum distortion to the leaves at their juncture with the binding, to provide a marker which is easily flexed and removable from one place in the book without disturbing the holding means or the positioning and security of other markers.

The invention also includes other features and improvements which will appear in the following description:

Referring to the drawings which illustrate the invention—

Fig. 1 is a perspective view of a book showing the holding means, and two markers in place;

Fig. 2 is a perspective view of the holding means shown in Fig. 1;

Fig. 3 is a perspective view of a modified form of the holding means;

Fig. 4 is a side elevation of a marker;

Fig. 5 is a plan view of the marker shown in Fig. 4;

Fig. 6 is a side elevation of modified form of marker;

Fig. 7 is a further modification of the holding means.

B represents a book having covers 1 attached to the binding 4 at the back of the book. The leaves 3 are attached to the binding. As is customary, the back 2 extends slightly above the tops of the leaves 3.

In certain uses to which books are put, it is sometimes desirable to have as many as thirty (30) markers placed between as many selected leaves of the book. These markers 5 may be of the type shown in Fig. 4 or the type shown in Fig. 6. The marker 5 is formed with a vertical portion 6 having outwardly forked ends 7 and an outwardly extending section 8. Attached on the outer extremity of 8 is a number or other indicating means which extends out beyond the edge of the leaves so as to be visible.

The marker shown in Fig. 4 consists of the same elements as the marker shown in Fig. 6, but differs from it in that the vertical section 6 has its two extremities bent to form parts 9. The purpose of this is to further remove the vertical section 6 from the binding 4, and hence to minimize the distortion of the leaves at that point. It is not desirable to have the extensions 9 too long, for the vertical section 6 must not extend out on the leaf so far as to cover up the printed matter appearing thereon.

By using the holding means described herein, it is possible to employ the type marker shown in Fig. 6, and obtain the advantage of the minimum distortion of the leaves of the binding, because the loop 10 is located to properly position the vertical section 6 of the marker out from the binding. This has not been true of the prior art type of marker holder, in which the tendency of the holding means, upon the book being opened, was to draw in the vertical section 6 until it contacted the binding, and then, when the book was closed, the two leaves between which the marker was positioned, would be badly strained at the point where they joined the binding. In many cases, the leaves have become loosened and fall from the book.

The holding means by which the markers are maintained in proper position consists of a retaining loop or bar 10, positioned to be engaged by the forked ends 7 of the markers. The loop 10 is shaped to conform to the direction of movement of the forked ends 7 of the markers when the leaves of the book are shifted from closed position to an open position, or vice versa. The proper shaping of the loop 10 is important, for it is preferable that at no time should the vertical section 6 of the marker be forced into harmful contact with the binding of the book when the leaves are closed. The retaining loop 10 is positioned slightly above the tops of the leaves by means of a bar 11 extending across the tops of the leaves in close contact with the end of the binding 4. It is important that the bar 11 be shaped or bent outwardly from the end of the binding to about the degree of curvature assumed by the binding when the book is lying open on a table. This curvature is also a guide to the proper shaping of the loop 10. The curvature at the end of the loop 10 will vary somewhat, depending on the thickness of the book, and can be easily determined by placing between several of the end leaves the markers 5, first observing the position of the forked end 7.

A marker retaining means, such as shown in Fig. 2, is used at each end of the book, and is maintained in position by means of the arms 13, which may be formed integral with the bar 11, or suitably attached thereto. A hook 14 is formed at the extremities of these arms 13, and a pair of suitable connecting

means, such as rubber bands 15, holds the two marker holders in place in the book. When the size of the book, in which the retaining means is to be used, is known by the manufacturer, the form of the device shown in Fig. 7 is preferred. In Fig. 7 is shown such a marker holding means.

The loop means are identical with that shown in Fig. 2, the only difference in this construction being that the connecting members 16 are spaced apart a distance determined by measuring the thickness of the pages of the book inside the covers. The length of the wires 16 is such that the two bars 11 will clear the tops of the leaves by the barest margin. Once in place, it is seldom ever removed until the book wears out.

The modification of holding means shown in Fig. 3 differs from that shown in Fig. 2 only in that the retaining loop 10a is so formed as to occupy a position farther removed from the tops of the leaves of the book. This modification is intended particularly for use with the marker shown in Fig. 4, and has particular advantage in those cases where it is desired to cause a minimum distortion of the leaves at or near the binding. The retaining loop 10a is raised above the leaves sufficiently that when the forked ends 7 of the marker shown in Fig. 4 are in place on the loop 10a, the lower part of the extensions 9 of the marker will avoid contact with the tops of the leaves.

By employing the invention described herein, it is possible for a student to quickly and easily change the position of the various markers without removing the marker holding means, and each marker is removed and placed in its new position without disturbing any other marker or markers that may be in place.

To change the position of a marker, it is grasped by the fingers, as shown in Fig. 6. The vertical section 6 being flexible, a slight upward or downward movement of the marker will disengage one of the forked ends 7 from the retaining loop 10. Movement in the opposite direction will release the other forked end and the marker is free to be placed in a new position in the book. In replacing the marker, the operations just described are reversed. One forked end is placed over the lower or upper retaining loop 10, and by means of the fingers grasping the marker, the vertical part 6 is buckled slightly, and the forked end 7 is slipped into place on the other retaining loop 10.

An advantage of the type marker shown in Fig. 4 is that in changing position, instead of having the finger grasp the bar 5 of the marker, the finger can engage the upright portion 6, at, or near, the bent portion 9.

It is contemplated that instead of wire, the holders may be made of other materials, such

as stampings or castings, from metal, bakelite, etc.

Having thus described my invention, what I claim and desire to secure by Letters Patent is—

1. In a bookmarker set, the combination of a marker comprising a flexible section shaped to extend along the inside edge of the page adjacent the binding, having outwardly

10 forked ends and a part extending out from the flexible section to beyond the edge of the sheet to indicate the position of the marker and a holder at each end of the book for positioning said marker in the book comprising

15 a retaining loop positioned to be engaged by said forked ends and shaped to follow the curve normally taken by said forked ends when the book is opened and closed, a bar fastened to said loop and resting on the tops

20 of the leaves, and means to connect the holders.

2. In a bookmarker set, the combination of a marker comprising a flexible section shaped to extend parallel to the inside edge of the

25 page but spaced out slightly from the binding so as not to bulge the book at that point, having outwardly forked ends and a part extending out from the flexible section to beyond the edge of the sheet to indicate the po-

30 sition of the marker, and a holder at each end of the book for positioning said marker in the book comprising a retaining loop positioned to be engaged by said forked ends and shaped to follow the curve normally taken by said

35 forked ends when the book is opened and closed, a bar fastened to said loop and resting on the tops of the leaves, and means to connect the holders.

3. In a bookmarker set, the combination of a marker comprising a flexible section having outwardly forked ends and a part extending out to indicate the position of the marker, and a holder at each end of the book for positioning said marker in the book comprising

45 a retaining loop positioned to be engaged by said forked ends, a bar fastened to said loop and resting on the tops of the leaves and means to connect the holders.

4. A bookmarker holder, comprising a holder at each end of the book for positioning markers in the book, having a retaining loop positioned to be engaged by the forked ends of a marker and shaped to follow the curve normally taken by said forked ends when the book is opened and closed, a bar fastened to said loop and resting on the tops of the leaves, and means to connect the holders.

5. A bookmarker holder, comprising a holder at each end of the book for positioning said marker in the book having retaining means positioned to be engaged by the forked ends of a marker, means attached to said retaining means and resting on the tops of the leaves, and resilient means to connect the holders.

6. A holder assembly, adapted to be placed at the top and bottom of book bindings, to retain place markers therein comprising two end plates, each shaped to rest on the top of the leaves over the binding and with a loop overlying, but spaced from, the leaves, to be engaged by the markers and means to hold said plates snugly against the tops of the leaves.

7. A bookmarker, suitable for being held in place by means of loops at each end of the book, comprising a flexible section with bent ends having open, outwardly forked ends lying between the loops, that part of the section which lies between the leaves being spaced slightly from the binding by said bent ends, and a part extending out from the flexible section to beyond the edge of the sheet to indicate the position of the marker.

8. A bookmarker, suitable for being held in place by means of loops at each end of the book, comprising a flexible section with open, outwardly forked bent ends lying between the loops, that part of the section which lies between the leaves being spaced slightly from the binding, and a part extending out from the flexible section to beyond the edge of the sheet to indicate the position of the marker, and a holder at each end of the book for positioning said marker in the book, comprising a retaining loop positioned far enough above the leaves to be engaged by the forked bent ends of the marker and hold them out of contact with the leaves of the latter's junction with the binding, a bar fas-

90 tened to said loop and resting on the tops of the leaves, and means to connect the holders.
